[57] CLAIM

The ornamental design for an ornamental belt buckle, as shown and described.

DESCRIPTION

FIG. 1 is a front elevational view of an ornamental belt buckle showing my design;

FIG. 2 is a top view;

FIG. 3 is a rear view thereof;

FIG. 4 is a front elevational view of a second modified ornamental belt buckle showing my design;

FIG. 5 is a top view thereof;

FIG. 6 is a rear view thereof;

FIG. 7 is a front elevational view of a third modified ornamental belt buckle showing my design;

FIG. 8 is a top view thereof;

FIG. 9 is a rear view thereof;

FIG. 10 is a bottom view of all the modifications of the ornamental belt buckle showing my design;

FIG. 11 is a right hand end view of all the modifications of the ornamental belt buckle showing my design, the left hand end view being identical thereto.
